SUPPORTING DEVICE

Application filed November 25, 1925. Serial No. 71,292.

The invention relates to mechanical movements and is particularly applicable to supporting devices, such as supporting devices for pipes, coils, radiators, cables, and the like.

An object of the invention is to provide in a mechanical support parts so arranged and combined that the supporting member will at the point of support operate through an absolutely horizontal plane although said member, which initially is vertically disposed, may in its operation diverge widely from said original, vertical disposition. The major member, to which the load is ultimately transferred through said supporting member, is so arranged as to divide the load between two curved or eccentric elements forming part of said major member. The load or weight is distributed to the curved or eccentric elements equally, when the supporting member is at rest or in normal neutral or vertical position, through two supporting members or arms connected to the supporting member or into which the latter may be divided, these supporting arms forming contacts with the said eccentric elements. When power application tends to disturb the normally vertical and initial position of the supporting member, there is a natural tendency to throw an ever increasing percentage of the load or weight onto one of the said supporting arms. The combination of the respective parts of the supporting device is such that, when action begins, whether in either direction, right or left, the supporting arm, on which the increased load is thrown and on which the gradual augmentation of load occurs, is on the decline of the given eccentric. Further, said combination is such that, should the action or movement of the initial support be so great as to carry it out of the vertical so far that the supporting arm has reached a contact point at the lower point of support in the eccentric, then the supporting member will have a leverage outside of the center line of said supporting member in its initial or vertical position, and in addition the supporting member will have risen and altered the ratio of leverage between the two effective elements of the supporting member,

that is the power arm and the load arm, in their relation to the eccentric members.

Another object of the invention is to provide a mechanical movement which may be included in a compact device and yet be capable of a comparatively wide range of operation.

A further object of the invention is to provide a supporting device which, while being capable of carrying a load will also permit a reciprocating movement of the load on a given straight line without harmful effects to either the supporting device or the load carried thereby and which further will tend to reduce the live load effect of the supporting member. Other objects of the invention are to provide a supporting device of this character which shall be simple in construction and operation and of high efficiency. These and other objects of the invention will be more fully set forth in the following description.

In the accompanying drawings, which are referred to herein and form part hereof, are several diagrams setting forth certain principles of the invention, and there are illustrated several embodiments of the invention as applied to supporting devices.

Of the drawings:

Fig. 1 is a front view of a supporting device constructed in accordance with certain principles of the invention and particularly devised for supporting radiators, piping or other equipment from walls or vertical surfaces;

Fig. 2 is a side view of the same, parts being broken away, and shows means for vertically adjusting the supporting device;

Fig. 3 is a top plan view of the device illustrated in Fig. 1, parts being omitted;

Fig. 4 is a diagram showing the plotting of the curves of the operative faces of the sustaining element shown in Fig. 1;

Fig. 5 is a front view of a supporting device for carrying pipes, cables, driving rods, bridges or other equipment requiring substantial support through a range of action;

Fig. 6 is a side view of the same;

Fig. 7 is a front view of a supporting device for carrying loads in general, the same

being a modification of the device shown in Figs. 1 and 5;

Fig. 8 is a side view of part of the construction shown in Fig. 7;

Fig. 9 is a plan view taken on the line 9—9 of Fig. 7 and looking in the direction of the arrows;

Fig. 10 is a view generally similar to Fig. 7, parts being broken away, but showing the load carrying parts in different positions; and

Fig. 11 is a diagrammatic view, in reverse to Fig. 4, and shows the plotting of the curves of the operative faces of the sustaining element shown in Fig. 7.

Referring now to the drawings in detail, and first to Figs. 1, 2, 3 and 4, there is illustrated therein a supporting device constructed in accordance with certain features of the invention, for carrying radiators, as on a wall. Considerable difficulty is experienced in supporting radiators on walls because of the very considerable pressure exerted by expansive or contracting action, the effect of these powers being exerted in a direction incident to the point of anchorage. The result of these forces will be to distort the radiator from the levels or grades originally established when uninfluenced by expansive or similar action, thus causing heavy strain which may cause leaks or fracture. There is a further necessity for supporting insulated piping on hangers which will permit the integrity of the insulation to remain intact through the life of the plant.

Means are provided, therefore, for supporting the piping, which means will permit forward movement of the piping without strain on the latter due to the nature of the supporting means and without injury to the said supporting means. In the embodiment of the invention illustrated in the drawings this means comprises a lever so constructed and arranged that one end thereof can move in a curved line while the other end, which supports the piping, will at the same time move in a straight line, as in a true horizontal plane. As shown in Figs. 1, 2 and 3, said means comprise a frame member 13 of suitable length and width, see Fig. 1, and having at its upper and lower ends inwardly turned portions 14, 15, respectively. By means of these portions, the body 13 of said member is spaced apart from the wall 17 to which it is fastened, as by bolts 18, 19 extending through orifices in flanges 21, 22 which flanges are formed at right angles to said curved members 14, 15, respectively. The body portion of said member 13 is formed with a longitudinal slot 23 therein for a purpose which will presently be described, said slot having at its lower end a quadrangular enlargement 24. A screw-threaded bolt 26 is arranged longitudinally between the member 13 and the wall 17, ex-

tending through the member 14 to which it is secured by a nut 27.

Arranged in front of said member 13 and in close proximity thereto is a lever 31, having a widened body portion 32 formed with a longitudinal slot 34 therein having a circular enlargement 36 at its lower end. Said body portion 32 is formed at its inner edges about the slot with a depressed portion 37. The lever 31 terminates at its upper part in an annular member 38 in which is fitted a bearing member 39, having a stub 41 closely engaging the inner surface of said annular member 38 and being of less diameter than the adjacent edge 42 of said member 39. At its end opposite said edge 42 said stub 41 is held in place in the annular member 38 by a disk 43 of greater diameter than said stub 41 and held in contact with the face of the member 38 by a nut 44, screwed on an extended threaded portion integral with said stub and projecting therefrom, all as clearly shown in Fig. 2. At its opposite end said member 39 is formed with a projecting bar terminating in a screw-threaded pin 45.

Preferably and as shown, see Fig. 1, the lever 31 is formed at its lower end with laterally diverging arms or bearing members 49, 50, bifurcated at their respective ends and provided with rollers 52, 53 mounted on said ends, as by means of pins 54, 55.

A fixed sustaining element 56 is arranged in close proximity to the face of the frame member 13, being held in place by a lug 57 extending through the slot 23 in said member 13, which lug is bored and internally threaded to engage the rod 26. Said sustaining element 56 is also provided with side flanges 58 and 59 engaging the sides of the frame member 13 and further securing the sustaining element in place and against lateral movement. Said cam is formed with laterally and upwardly extending wings 61, 62 having inner oppositely disposed operative faces 63, 64 preferably and as shown equally curved from a common center 66 from which they descend and then rise as shown in Fig. 1, each of the faces 63, 64, as shown, having thus associated with it a supplementary oppositely inclined face. On these faces 63, 64 the lever 31 is supported and oscillates by means of the rollers 52, 53 in a manner presently to be described.

The radiator sections are hung upon the bearing members 39, being vertically disposed with relation thereto, as indicated by the dotted lines in Fig. 3, the ends of the sections being joined in the conventional manner, not shown, and the sections resting upon the bearing members. It will be observed that the load will be finally distributed through the arms 49, 50 of the lever 31 equally upon the sustaining element faces 63, 64, the lever 31 being normally centrally and vertically disposed upon the sustaining ele-

ment 56, the points of contact of the rollers 52, 53 upon the faces 63, 64 of the sustaining element being equidistant from the central point 66. When the radiator, piping or other supported unit under positive action or that of contraction or expansion moves laterally as in the direction of the arrows in Fig. 1, there will be a stress exerted upon the support, and subsequently the supported unit, because of the engagement of the piping to the bearing member of the supporting device, and if these supporting devices were immovable or of a type which would swing from a fixed center and thus disturb the alignment or were of a type similar to that of a roller with a small radius, the stress incident thereto would result in distortion and probable leaks and would further result in the destruction of the insulation, should the supported unit be provided with any. By mounting the lever 31 with a rolling contact upon the operative faces of the fixed sustaining element, as shown in Fig. 1, however, the upper end of the lever 31 with the supporting members 39, is enabled to move with the piping and in a true horizontal plane. For, see Fig. 1, as the upper end of the lever moves to the right, the load on the arm 50 and roller 53 will be instantly increased, with a compensating diminution of the load on the arm 49 and roller 52. The roller 53 will descend but in a gradual manner due to the nature of the curve of the face 64, the descent being further safeguarded and checked because of the ascent on the curved face 63 of the arm 49 and roller 52. Because of the equality of the curves 63 and 64, the ascent of the roller 52 will correspond exactly to the descent of the roller 53. As the expansive pressure or positive action subsides, it will be seen that there will be a movement of the lever 31 in the reverse direction.

Means are provided for guiding and limiting the lateral movement of the lever 31, said means, as shown, see Figs. 1 and 2, comprising a pin 67 fastened by means of a bored and internally threaded lug 68 to the threaded rod 26 and projecting through the slot 23 in the frame member 13 and the slot 34 in the body portion 32 of the lever 31. Said pin 67 is provided at its outer end with a circular flange 69 engaging the face of said body 32. It will be seen that as the lever 31 moves laterally from its central position, it will move up and down on the pin 67, thus preserving the supporting point in a true horizontal plane and providing for the variable in the leverage, as desired. The parts will be so constructed as to permit sufficient movement to answer the requirements of any particular case. The action of the lever 31 is diagrammatically illustrated in Fig. 4 in which the relative positions of the lever top and the rollers after various degrees of move-

ment are shown. For example, when the top of the lever, as shown by the circle 71 has been moved to the right to the point 72, the rollers will have moved from the positions shown in Fig. 4 to positions indicated by the respective curves immediately to the left, and so on. And it is to be noted that without any deformation of the lever or change in its length while its lower ends have been moving in curved paths, its upper end has been traversing a true horizontal plane. The method of determining the lines of the bearing element employed in the preferred form is clearly indicated in Fig. 4. The impinging point between the load carrying element 31 and the load is in this instance at 71, Fig. 4, wherein said point 71 is made to describe a straight line in the direction of 71 to 72 or the reverse and in accord with the functions of the device. At one end of the lever 31, Fig. 4, is indicated the forked part including the respective points of support of the bearing element referred to. At point 67, Fig. 4, is provided a pivot constantly in a plane parallel with the direction of impulse. The lever 31 is suitably slotted to engage this pin 67 and slide upon it, thus permitting the compensation necessary in the action of the impinging point 71 of the lever 31 in following the straight line 71 toward 72 or the reverse. The lower point of the lever 31 is further provided with a forked element, the length of each fork and the distance apart of the forks being dependent on the required length of travel at 71 toward 72, or reverse, as is also the distance of the pin 67 from the point 71 and from the extremities of the forks. It will be observed, see Fig. 1, that these forked extremities are indicated therein at the contact points in the preferred form of the rolls 52 and 53 with the sustaining elements 63 and 64.

It will be observed that in the event of the load traveling in the direction indicated by the arrow, Fig. 1, or from 71 toward 72 or the reverse, Fig. 4, there will be a natural tendency to throw the applied effort on the lever 31, Fig. 1, to the fork 50, and that the effective effort thus applied at that point is on the decline of the sustaining element 62, Fig. 1, until the valley is reached at a point approximating 64, Fig. 1. Continued action in the direction of the arrow 2, Fig. 1, or the line 71—72, Fig. 4, will result in the device exceeding its established cycle of operation and climbing the respective sides indicated at the left of the two sustaining elements shown in their preferential form at 61 and 62, Fig. 1. To effect this without destroying the device and with comparative ease, the ratio of leverage length included between the pin 67 and the impinging point 71, Fig. 4, and the corresponding effective length of leverage between the pin 67 and the rolls 52 and 53, Fig. 1, is materially altered, as is

indicated in the relative distance between the pin 67 and the impinging point 71, when in the central or normal position as shown, compared with the length of this lever when extended in travel through the length of operation from, say, 71 toward 72, or the reverse and as indicated by the distance between 67 and 72, Fig. 4. It will be observed that inasmuch as the compensation is effected through the using of the lever 31, Fig. 1 or Fig. 4, in relation to the pin 67, there is a consequent diminution of the leverage length in the forked element, thus increasing the power application in the moving load as described.

It will be noted that the device can be adjusted vertically to permit varying heights of the radiators by adjusting the pin 67 and sustaining element 56 on the rod 26, which adjustment is done simultaneously through turning in the proper direction the rod 26.

A modification of the invention is shown in Figs. 5 and 6, wherein is illustrated a supporting device used for carrying pipes under the influence of contraction or expansion or that of applied power. It is a common practice in plants using steam power to generate the steam in one building and convey it to other buildings of the plant through pipes housed in conduits. The same difficulty is experienced in suspending the pipes in the conduits as has been described with reference to the supporting of radiators or coils on walls because of the very considerable pressure exerted by the expansive or power element in the direction of the length of the pipes and the necessity for flexibility in the supports for the pipes. In this modification of the invention, as shown, see Fig. 5, there is provided a base 74 securely anchored by bolts 76 to the floor of the conduit. Rising from said base is a framework comprising front and rear plates 13^a, 13^b having projecting lugs 77 bored and retaining four screw-threaded rods 78. Above the said top lugs are bolt heads 82. Said plates 13^a and 13^b are formed with depressed portions 32^a extending longitudinally throughout the upper portions of said plates, the undepressed portions forming edges 37^a about said depressed portions. Said depressed portions are formed with longitudinal slots 34^a therein. A sustaining element 56^a, in the main similar to the sustaining element 56 heretofore described, is arranged between the plates 13^a and 13^b and is secured to the rods 78 by bored and internally threaded lugs 57^a. A lever 31^a generally similar to the lever 31 is arranged between said plates 13^a and 13^b to oscillate upon the operative faces of said sustaining element 56^a. The pin 67^a, however, which guides and limits the lever 31^a in its movement is in this embodiment of the invention formed on one end with a slotted head member, the bottom of which is provided

with teeth 67^b arranged to engage similar teeth 67^c on the depressed face 32^a of the plate 13^a and thus hold said pin in proper position; said pin, which extends thru the slots 34^a in the plates 13^a and 13^b, being screw threaded on its opposite end, on which end is screwed a nut, which is shown in dotted lines and a full line in Fig. 5, and which nut closely engages the depressed portion 32^a of the plate 13^a. At its upper end the lever 31^a is formed with outwardly curving arms 83 within which is arranged a semi-circular cradle 84 swinging on pins 86 extending through slots 87 in the rounded ends of the arms 83, as shown in Figs. 5 and 6. In this cradle 84 rests the pipe 88, as indicated in dotted lines in Fig. 6. It is to be noted that the sustaining element 56^a may be raised or lowered on the rods 78 as desired, and the position of the pipe 88 changed accordingly. The operation of the device is similar to that of the support heretofore described and shown in Figs. 1, 2 and 3.

In Figs. 7 to 10, inclusive, is shown another modification of the invention, in which the arrangement of the lever is the reverse of that shown in the preceding modifications. This modification is capable of application to a variety of uses and may be used for carrying pipes, subject to expansion or contraction as is the modification shown in Figs. 5 and 6, the pipe in this instance being represented by the weight marked W in Fig. 7. An I-beam 90 or other support is used at the upper part of the conduit or the structural beam in any construction may be used and a plate 91 is clamped thereto by clamping screws 92, passing through slots 93 which are extended longitudinally to permit adjustment to varying sizes of I-beams, all as clearly shown in Fig. 7. Depending from the under side of the plate 91 and formed integrally therewith are annular lugs 94, one at each corner of said plate which are interiorly and laterally recessed, see Figs. 7, 8 and 9, to receive the heads 96 of bolts 97, the lateral recesses in the lugs on one side of the plate extending in a direction opposite to that taken by the lateral recesses in the lugs on the opposite side, thus preventing any possibility of the bolts 97 slipping from their positions. At their lower ends said bolts 97 are fastened to a sustaining element 98, having wings 99, 100 by means of bored and threaded lugs 101, two of said lugs being on each side of said sustaining element and, as shown, on the wing portion thereof. Said sustaining element is formed with a slot 102 extending throughout the greater portion of its length, see the dotted lines in Figs. 7 and 10, in which slot is arranged normally in vertical position a lever 103, having at its upper end a transverse arm 104 terminating in bifurcated ends in which are arranged rollers 52^b, 53^b by means of pins 54^b and 55^b. The load in this embodiment of the invention

instead of being applied at the top of the lever is applied at the bottom of the lever. The curves 63^b and 64^b of the operative faces of the sustaining element 98 are therefore convex instead of concave but the reciprocating 5 laterally in a horizontal plane of the lower end of the lever 103, while the rollers 52^b, 53^b move up and down on their respective faces, is the same as in the modifications of the invention heretofore described. The various degrees of movement of the lower end 10 of the lever in the horizontal plane and the corresponding moves in curves of the rollers are diagrammatically shown in Fig. 11, a 15 movement to the right from point 106 to point 107 by the end of the lever being accompanied by a movement of one roller from point 108 to point 109 and by a movement of the other roller from point 111 to point 112. The diagram Fig. 11 is described in substantially the same manner as that of Fig. 4. In this type 20 of support the load is suspended beneath the load carrying element, and the supporting lever 103, Fig. 10, is not continued beyond the forked element.

In this particular form, however, where the load is suspended, as in Fig. 10, there are indicated two distinct acts of weight transfer due to the shifting of the center of gravity 30 and involving a complete cycle of operation of the thus freely swung member, with the incident variation of leverage ratio included. Thus, further, as in Fig. 10, the effective leverage is through what is in effect a three 35 point suspension member; and when in action, the leverage shifts from the contact point of one arm to that of the other, according to the direction of motion; and the load impulse or effective effort is thus always converted to a downward direction. This effective effort may be defined as the energy exerted in moving and in effect upsetting the load plus the momentary preponderance of load thus imposed at any given point.

In Figs. 7, 10 is clearly shown the shifting 45 of the center of gravity by which ease of operation and elimination of strain on the unit or its anchorage is eliminated. For instance, in Fig. 7 it is clearly shown that the load or weight W has its weight evenly distributed and that the center of gravity, when inactive, is through the center of the device on the lever 103. In Fig. 10 the center of gravity, when inactive, is shown to have shifted, according 50 to the degree of operation of the device, to a line closely approximating a vertical, drawn through the center of the orifice at the lower end of 103 and the pin on which the roller 53^b operates; while in action, however, it will 55 be observed that the load is thrown on the wing of the support following the direction of travel, this by reason of the upsetting effect of the three-point support. At the same time the dead weight will tend to preserve the unit 60 in equilibrium.

It will be seen that a mechanical movement constructed in accordance with the principles of the invention will be capable of application to many uses and will possess many advantages, which will be apparent to those skilled 70 in the art.

The invention in its broader aspects is not limited to the precise constructions shown and described, as many changes may be made in the details thereof adapting it to other uses, 75 as for example, to supports for bridges, without departing from the main principles of the invention or sacrificing its chief advantages.

I claim:

1. A mechanical movement including in combination, a sustaining element having a pair of curved operative faces oppositely disposed, a lever normally perpendicularly arranged with relation to said sustaining element, and means connected with two opposite sides of said lever and movably bearing upon said sustaining element faces, whereby said lever may be moved laterally with its end remote from said connecting and bearing means moving in a line parallel to a given straight line.

2. A mechanical movement including in combination, a sustaining element having a pair of curved operative faces oppositely disposed, a lever normally vertically arranged with relation to said sustaining element, and means connected with two opposite sides of said lever and movably bearing upon said sustaining element faces, whereby said lever may be moved laterally with its end remote from said connecting and bearing means moving in a line parallel to a horizontal line.

3. A mechanical movement including in combination, a relatively fixed element having a pair of curved operative faces oppositely disposed, a lever movable with relation to said element and normally vertically disposed with relation thereto, a pair of members arranged on the opposite sides of said element, and means affording a sliding or rolling contact between said pair of members and said element.

4. A supporting device including in combination, a sustaining element having curved operative faces oppositely disposed, means for supporting said sustaining element, a lever normally vertically disposed with relation to said sustaining element and arranged at one portion to engage a load, and bearing members connected to another portion of said lever and adapted movably to engage said faces, whereby said lever may be moved laterally with its load bearing portion moving in a line parallel to the horizontal.

5. A supporting device including in combination, a sustaining element having curved operative faces oppositely disposed, means for supporting said sustaining element, a

supporting element having portions movably engaging opposite operative faces of said sustaining element, and means connected to said supporting element and arranged to engage a load, whereby said supporting element may be moved laterally with its load bearing portion moving in a line parallel to a given straight line.

6. A supporting device including in combination, a frame, a sustaining element arranged on said frame and having oppositely curved operative faces, and a lever normally vertically disposed with relation to said sustaining element and arranged to oscillate thereon, said lever being arranged at one end to carry a load and at the other end having arms adapted to move on said sustaining element faces, whereby in the oscillation of said lever said arms will describe the curves of said sustaining element faces while the load-carrying end of said lever will move in a straight line.

7. A supporting device including in combination, a frame member formed with a longitudinal slot therethrough, a sustaining element with curved operative faces secured to said frame, a lever with arms at one end arranged to oscillate on said sustaining element faces, said lever being formed with a longitudinal slot therethrough, and a member secured to said frame and extending through both said slots for guiding and limiting the movement of said lever.

8. A supporting device including in combination, a frame member formed with a longitudinal slot therethrough, a sustaining element with curved operative faces adjustably secured to said frame, a lever with arms at one end arranged to oscillate on said sustaining element faces, said lever being formed with a longitudinal slot therethrough, and a member adjustably secured to said frame and extending through both said slots for guiding and limiting the movement of said lever.

9. A supporting device including in combination, an anchored frame, a sustaining element with curved operative faces secured to said frame, a lever with arms at one end arranged to oscillate on said sustaining element faces, said lever being formed with a longitudinal slot therethrough, and a member secured to said frame and extending through said slot for guiding and limiting the movement of said lever.

10. A supporting device including in combination, a sustaining element having oppositely curved operative faces, and a lever normally vertically disposed with relation to said sustaining element and arranged to oscillate thereon, said lever being arranged at one end to carry a load and at the other end having arms adapted to move on the respective sustaining element faces, whereby in the oscillation of said lever said arms will de-

scribe the curves of said sustaining element faces while the load-carrying end of said lever will move in a horizontal plane, the horizontal movement causing a rising movement of the arm on the sustaining element face in the opposite direction and thereby increasing the ratio which the length of the power arm of said lever bears to the entire length of said lever.

11. A supporting device including in combination, a sustaining element having oppositely curved operative faces, and a lever normally vertically disposed with relation to said sustaining element and arranged to oscillate thereon, said lever being arranged at one end to carry a load and at the other end having arms adapted to move on the respective sustaining element faces, whereby in the oscillation of said lever said arms will describe the curves of said sustaining element faces while the load-carrying end of said lever will move in a horizontal plane, the increased leverage required for the ascending movement of the arms on the sustaining element faces being provided by the horizontal movement of the load-carrying end of the lever and being proportional thereto.

12. A mechanical movement including in combination, a relatively fixed element having a pair of inclined operative faces oppositely disposed, an oscillatory lever cooperating with said element and normally vertically disposed with relation thereto, a pair of members arranged on the opposite sides of said element, and means affording a sliding or rolling contact between said pair of members and said element.

13. A mechanical movement including in combination, a supporting structure, a pair of oppositely disposed constantly inclined faces, a lever element normally perpendicularly arranged with relation to said faces, and means connected with two opposite sides of said lever element at one end and arranged movably to bear upon said faces, the opposite end of said lever element being arranged to have weight-power applied thereto, and said faces and lever element being supported on said supporting structure, said lever element being arranged to oscillate so that while said opposite end of said lever element is moving in a straight line, the other end of said lever element at the point of immediate preponderant imposed weight-power will be given a downward direction.

14. A mechanical movement including in combination, a supporting structure, a pair of oppositely disposed inclined faces, a lever element normally perpendicularly arranged with relation to said faces, means connected with two opposite sides of said lever element at one end and arranged movably to bear upon said faces, the opposite end of said lever element being arranged to have weight-power applied thereto, and said faces

and lever element being supported on said supporting structure, said lever element being arranged to oscillate so that while said opposite end of said lever element is moving in a straight line, the other end of said lever element at the point of immediate preponderant imposed weight-power will be given a downward direction, and supplementary faces associated one with each of said first-named faces and oppositely inclined thereto, on one of which supplementary faces said last-named part will move upwardly when the device, having completed its normal limit of action in said downward movement, is operated in excess thereof.

15. 15. A supporting device including in combination a frame, a sustaining element arranged on said frame and having oppositely inclined operative faces, a lever normally perpendicularly disposed with relation to said sustaining element and arranged to oscillate thereon, said lever being arranged at one end to carry a load and at the other end having arms adapted to move on said faces, and supplementary faces associated one with each of said first-named faces and oppositely inclined thereto, on one of which supplementary faces one of said arms will move upwardly when the device is operated in excess of its normal limit of action.

20. 16. A supporting device including in combination, a frame, a sustaining element adjustably arranged on said frame and having oppositely curved operative faces, and a lever normally vertically disposed with relation to said sustaining element and arranged to oscillate thereon, said lever being arranged at one end to carry a load and at the other end having arms adapted to move on said sustaining element faces, whereby in the oscillation of said lever said arms will describe the curves of said sustaining element faces while the load-carrying end of said lever will move in a straight line.

25. 17. A supporting device including in combination, a frame, a sustaining element arranged on said frame and having oppositely curved operative faces, and a lever normally vertically disposed with relation to said sustaining element and arranged to oscillate thereon, said lever being provided at one end with a rocking cradle to carry a load and at the other end having arms adapted to move on said sustaining element faces, whereby in the oscillation of said lever said arms will describe the curves of said sustaining element faces while the load-carrying end of said lever will move in a straight line.

30. 18. A supporting device including in combination, a frame, a sustaining element arranged on said frame and having oppositely curved operative faces, said element being formed with a slot extending throughout the greater part of its length, and a lever normally perpendicularly disposed in said slot

and arranged to oscillate therein, said lever being arranged at one end to carry a load and at the other end having arms adapted to move on said sustaining element faces, whereby in the oscillation of said lever said arms will describe the curves of said sustaining element faces while the load-carrying end of said lever will move in a straight line.

35. 19. A supporting device including in combination, a pair of bearings to sustain a load, an oscillating lever having parts arranged movably to bear upon said bearings and a portion adapted to have weight-power applied thereto, said lever being so arranged in relation to said bearings that during its entire actual movement of oscillation the immediate preponderant weight-power will be imposed upon one of said parts of the lever bearing upon said bearings, which said part will move in a downward direction, while the other said portion of the lever will move in a straight line.

40. 20. A mechanical movement including in combination, a relatively fixed element having a pair of inclined operative faces oppositely disposed, an oscillatory lever cooperating with said element and normally vertically disposed with relation thereto, a pair of members associated with said lever and arranged on the opposite sides of said element, and means affording a sliding or rolling contact between said bearing members and said element.

In testimony whereof, I have affixed my signature hereto.

GEORGE T. MOTT.
